The ornamental design for a notebook computer with light emitting parts, as shown and described.

DESCRIPTION

FIG. 1 is a front perspective view of the notebook computer with light emitting parts according to the claimed design, with the notebook computer in an open position;

FIG. 2 is a top view of the notebook computer with light emitting parts according to the claimed design, with the notebook computer in the open position;

FIG. 3 is a bottom view of the notebook computer with light emitting parts according to the claimed design, with the notebook computer in the open position;

FIG. 4 is a front view of the notebook computer with light emitting parts according to the claimed design, with the notebook computer in the open position;

FIG. 5 is a rear view of the notebook computer with light emitting parts according to the claimed design, with the notebook computer in the open position;

FIG. 6 is a left side view of the notebook computer with light emitting parts according to the claimed design, with the notebook computer in the open position;

FIG. 7 is a right side view of the notebook computer with light emitting parts according to the claimed design, with the notebook computer in the open position;

FIG. 8 is a partially enlarged view, as defined by lines A, B in FIG. 2, of the notebook computer with light emitting parts according to the claimed design;

FIG. 9 is a partially enlarged view, as defined by lines A and B in FIG. 2, of the notebook computer with light emitting parts according to the claimed design, illustrating an example of an illuminated state where all the light emitting parts are illuminated; and,

FIG. 10 is a partially enlarged view, as defined by lines A and B in FIG. 2, of the notebook computer with light emitting parts according to the claimed design, illustrating another
